INVENTOR
Melbourne White

UNITED STATES PATENT OFFICE.

MELBOURNE W. WHITE, OF CLIFTONDALE, MASSACHUSETTS, ASSIGNOR TO UNITED SHOE MACHINERY CORPORATION, OF PATERSON, NEW JERSEY, A CORPORATION OF NEW JERSEY.

LAST.

1,404,252.

Specification of Letters Patent. Patented Jan. 24, 1922.

Application filed August 1, 1918. Serial No. 247,779.

To all whom it may concern:

Be it known that I, MELBOURNE W. WHITE, a citizen of the United States, residing at Cliftondale, in the county of Essex and State 5 of Massachusetts, have invented certain Improvements in Lasts, of which the following description, in connection with the accompanying drawings, is a specification, like reference characters on the drawings indicating like parts in the several figures.

The present invention relates to lasts and more especially to lasts of the kind employed in forming and making shoes.

According to one method of attaching 15 heels to shoes, and particularly attaching wooden heels to shoes, the last upon which the shoe is being made is withdrawn from the shoe and the heel is attached by heel attaching nails driven from the interior of the 20 shoe outwardly into the heel after which the last is again inserted for subsequent operations on the shoe. This process of attaching heels, which is known as inside nailing, is open to the serious objection that, in with- 25 drawing the last from the shoe to enable the heel attaching operation to be performed and again relasting the shoe, considerable time and labor are involved and, also, the shoe is subjected to severe strain and dis- 30 tortion, so much so, in many instances, that it is found necessary to repair the shoe. Moreover, with certain types of shoes, as for example, vulcanized rubber soled shoes having wood heels, in its application to the 35 manufacture of which shoes the present invention is herein shown for purposes of illustration, the practice of the inside nailing process is especially difficult and impractical because the shoe parts are only temporarily 40 secured together by cement at the time the last is withdrawn for the heel attaching operation to be performed.

An object of the present invention is to provide a shoe forming and making last 45 which will be so constructed and arranged as to obviate the necessity of removing the last, or possibly the heel portion thereof, from the shoe to permit a heel to be attached by inside nailing and also, to effect the at- 50 tachment of the heel to the shoe by one or more heel attaching fastenings.

To this end, the present invention pro- 55 vides a novel shoe forming and making last comprising a forepart and a heel part, and having a fastening guiding passage formed

in the heel part and means associated with the said fastening guiding passage constructed and arranged to be operated to drive a heel attaching fastening from the fastening guiding passage into the shoe. 60 For this purpose the heel part of the last is constructed so as to provide a housing for the fastening driving means which, as herein illustrated, consists of a driver normally retained in inoperative relation to the fasten- 65 ing guiding passage and arranged to receive an actuating force which will cause it to project the heel attaching fastening from the fastening passage into the shoe. While any suitable means may be employed to pro- 70 ject the fastening driver in the fastening guiding passage to insert the fastening, the illustrated preferred embodiment of the invention contemplates the employment of a machine similar for example to that shown 75 in Patent No. 1,081,917, granted Dec. 16, 1913, on application of Eliphilet A. Tripp, to effect the operation of the driver. To this end, and as herein illustrated, the cone por- 80 tion of the heel part of the last is so con- 85 structed and arranged as to provide access to the driver which is housed within the heel part to enable the driver to be actuated. In the illustrated embodiment of the invention a gang of driver guiding passages is pro- 90 vided in the heel part and a gang of drivers, also housed within the heel part, is received in the driver guiding passages, the purpose of the gang mechanism being, however, merely to enable a sufficient number of fas- 95 tenings to be inserted properly to attach the heel in a single operation. It will be appreciated that the provision of a fastening guiding passage and the associated fastening driver in the heel part of the last enable 100 the heel to be attached to the shoe without disturbing the assembly of the shoe parts on the last and also it eliminates the last removing and shoe relasting operations which were necessary with the lasts heretofore used. 105

Other objects and features of the invention will be apparent from the following description when considered in connection with the accompanying drawings and the novel features of the invention will be de- 110 fined in the claims.

Fig. 1 illustrates in perspective a preferred embodiment of the last of the present invention, the heel part of the last being cut away to show the heel attaching mechanism. 110

Fig. 2 is a transverse section through the heel part of a last upon which a shoe is assembled ready for the heel attaching operation.

5 Fig. 3 is a side elevation of a portion of a machine which may conveniently be used in conjunction with the last of the invention, the last and manner of operation of the illustrated machine in connection therewith being shown.

10 The illustrated embodiment of the last is particularly adapted to the manufacture of vulcanized rubber soled shoes having wooden heels and accordingly the last is 15 made of metal to resist the vulcanizing heat to which it is subjected during the manufacture of the shoe. This metal last is preferably hollow and comprises a forepart portion 2 and an integral heel part 4 substantially the same as a wooden block last for 20 a leather shoe. It is desirable to attach wooden heels to vulcanized rubber soled shoes prior to the vulcanization of the shoe, both because of the difficulties encountered 25 in forming the proper heel seat on the shoe to receive the heel after the shoe is vulcanized and to secure the benefit of the vulcanized attachment of the heel to the shoe where it is seated on the rubber portions 30 of the shoe. Furthermore, when applying the heel to the shoe before vulcanization, it is important that the heel be seated firmly on the heel seat, otherwise the process of vulcanization tends so to upset and distort 35 the heel seat as to displace the heel on the shoe. Heretofore only an insecure attachment of the heel to the shoe was possible without withdrawing the last from the shoe and this could not readily be done without 40 straining the shoe upper which was held together by cemented seams.

45 In accordance with the present invention it is proposed to attach the heel to the shoe prior to its vulcanization with heel attaching nails inserted by mechanism mounted in the heel part of the last, thereby obviating the necessity of withdrawing the last from the shoe. The illustrated manner of 50 accomplishing this is to provide the heel seat wall 6 of the heel part of the last with a plurality of holes 8 arranged centrally of the heel seat surface of the last in any suitable design, as shown for example in Fig. 55 1. These holes 8 receive the ends of a plurality of metal tubes 10 rigidly held therein and projecting substantially vertically of the outer heel seat surface of the wall 6 into the hollow interior of the heel part 4, these tubes being provided with driver guiding 60 passages of a diameter to accommodate the size of the nails which it is desired to insert. Also housed within the heel part 4 is the means for projecting the nails received in the guiding passages 10 into the heel. This 65 means consists of a gang of drivers 12

mounted in a driver carrying bar 16. The drivers are preferably so mounted in the heel part in their normal inoperative position that a portion of each driver projects into its respective driver guiding passage in 70 the tube 10 so as to provide a seat for the nails in the passage in the inverted position of the last. The driver carrying bar 16 is additionally guided for reciprocation in the heel part 4 by guide rods 18 the upper ends 75 of which are rigidly secured in the heel seat wall 6 and project through holes provided in the driver carrying bar. For the purpose of retaining the driver carrying bar so that the drivers 12 occupy a normally retracted 80 or inoperative position in the guiding passages springs 20 surrounding the guiding rods 18 hold the driver bar against a shoulder 22 formed on the inner wall of the heel part 4. While the driver carrying bar 16 85 could conveniently be so arranged as to project through the cone portion of the last for the purpose of actuating the drivers 12 to drive the heel attaching nails, the proposed use of the last in conjunction with a machine 90 like that shown in the above identified Tripp patent involves the provision of a means of communication or access through the cone portion of the heel part to the driver carrying bar 16. Accordingly and as illustrated, 95 the cone portion of the heel part is provided with a rectangularly shaped hole 24 which extends substantially vertically through the heel part and in alignment with the drivers 12, this hole being somewhat smaller than 100 the rectangular driver carrying bar to enable the inner wall of the heel part to provide the shoulder 22 on which the driver carrying bar 16 is seated in its normal inoperative position.

105 In the use of the last above described, the shoe upper 26 and the insole 28 are first assembled on the last in the usual manner of making vulcanized rubber soled shoes 110 the nail receiving passages in the tubes 10 being previously loaded with heel attaching nails 30. Heretofore in locating the insole upon the last considerable trouble was occasioned by the insole becoming displaced on the last when the upper was lasted over upon it, this being due to the fact that since the last is made of metal there was no opportunity for fastening the insole to the bottom of the last by tacks as with a wooden last. With the last of the invention one, at least, 115 of the heel nails 30 which are placed in the nail passages is preferably of sufficient length to project a distance above the bottom of the last as indicated in Fig. 2. This projecting end of the nail thus serves as a 120 spur upon which to drive the heel end of the insole and hold it on the bottom of the last against displacement during the operation of lasting the shoe. The heel 32 is then properly positioned on the heel seat and the last 125 130

placed in inverted position upon the work support 34 provided by the machine, employed to operate the driver mechanism carried by the last. The illustrated machine for this purpose is provided with a reciprocatory driver operating bar 36 projecting through the work support 34 and the hole 24 in the cone portion of the last. The reciprocatory driver operating bar is preferably rectangular in cross section and has a running fit in the hole 24 of the last so that it also serves as a last pin to hold the last in position on the work support. To resist the driving force of the drivers 12 in inserting the nails into the heel, and also to clamp the heel 32 firmly onto the shoe the machine is provided with an adjustable block 37 which engages the top lift of the heel and with an adjustable clamp 38 which engages the side of the heel at the rear. The driver actuating bar 36 of the machine is conveniently operated through connections with a power-operated shaft as shown in the patent above mentioned. The actuation of this driver bar projects the drivers 12 in the driver guiding passages in the tubes 10 and drives the nails 30 from the passages into the heel as indicated in Fig. 3. Upon the withdrawal of the driver bar 36 into inoperative position, the drivers in the heel part of the last are returned to inoperative position by the springs 20, acting upon the driver carrying bar 16.

It will thus be noted that the heel may be attached to the shoe with accuracy and facility and without necessitating the removal of the last with its resulting disadvantages. Moreover, inasmuch as the heel can be applied to the shoe before vulcanization by the use of the last of the invention, a neater and more uniform attachment of the heel is obtained because the heel seat of the shoe is, before vulcanization, more or less conformable and, therefore, adaptable to the heel seat surface presented by the heel when the clamping pressure of the machine is applied. Incidentally the conformation of the seat to the heel insures a better adhesion and relation between the heel and heel seat of the shoe and consequently a stronger vulcanized connection is obtained.

While the term "heel attaching nails" is herein used, it is to be understood that this term is used generically to cover other kinds of heel attaching fastening, as for example screws. It is further to be understood that while the invention is herein illustrated as applied to a last of the type used in the manufacture of vulcanized rubber soled shoes and adapted for insertion of a gang of fastenings, the invention is equally well adapted for embodiment in a last of the kind used in the process of making leather shoes and to insert only a single heel attaching fastening if desired. It is still further to be understood that the last of the present in-

vention is in no way restricted in its specific construction to use in conjunction with the machine illustrated.

Having fully described my invention, what I claim as new and desire to secure by Letters Patent of the United States is:

1. A shoe forming last comprising a fore-part and a heel part and having a fastening receiving passage formed in the heel part, and means associated with the said fastening passage and contained within the body of the last, constructed and arranged to be acted upon by a last pin to drive a fastening from the fastening receiving passage into a shoe without removal of the shoe from the last.

2. A shoe forming last comprising a fore-part and a heel part and having a plurality of fastening receiving passages extending transversely of the heel part from its bottom surface, a plurality of drivers disposed in the fastening receiving passages, and driver connecting means located within the body of the last and constructed and arranged to be operated to drive heel attaching fastenings from the fastening receiving passages into a shoe without removal of the shoe from the last, said last having an opening in the last cone to permit access to the driver connecting means for operating the drivers as set forth.

3. A shoe forming last comprising a fore-part and a heel part conforming to the shape of the shoe to be lasted thereon, said last having a gang of driver guiding passages extending transversely of the heel part from its bottom surface, and a gang of drivers constructed and arranged in the body of the heel part for operation in the driver guiding passages, said last having an opening permitting access to said drivers so that they can be operated to drive heel attaching fastenings into the heel of a shoe on the last without removal of the shoe from the last.

4. A shoe forming last comprising a fore-part and a heel part and having a gang of driver guiding passages extending vertically of the heel part from its bottom surface, a gang of drivers positioned in the driver guiding passages, means located in the body of the last for normally holding the drivers in retracted position, and driver connecting means located in the body of the last and constructed and arranged for operative movement to drive a gang of heel attaching nails into the heel of a shoe.

5. A shoe forming last comprising a fore-part and a heel part, said parts corresponding fully to the shape of the shoe to be lasted thereon, the heel part being provided with a gang of driver guiding passages extending perpendicularly to its bottom surface, a gang of drivers housed within the heel part between the heel-seat and the cone of the last

and in alinement with said passages, said cone having an opening corresponding in location to the usual last pin hole, and means positively connecting the drivers of the gang 5 whereby their simultaneous operation may be effected by the insertion of an instrument through the hole in the last cone.

6. A shoe forming last comprising a fore-part, a heel part provided with a gang of 10 driver guiding passages extending vertically of the heel part from its bottom surface, a gang of drivers and driver connecting means housed within the heel part in alinement with said passages, and means 15 acting on the connecting means to hold the gang of drivers in retracted position in the heel part.

7. A shoe forming last comprising a fore-part, a heel part provided with a gang of 20 driver guiding passages extending vertically of the heel part from its bottom surface, and a gang of drivers housed within the heel part in alinement with said passages, and means to hold the gang of drivers 25 in retracted position in the heel part, said heel part being constructed and arranged to provide access through the last cone to the gang of drivers to actuate them.

8. A shoe forming last comprising a fore-part and a heel part and having a gang of 30 driver guiding passages extending vertically of the heel part from its bottom surface, a gang of drivers mounted in the heel part for operative movement in the driver guiding passages, and springs for holding the drivers in retracted positions in the driver guiding passages, said gang of drivers being accessible through the cone portion of the heel part to effect their operation in 35 open position to the said springs.

9. A shoe forming last comprising a fore-part and a hollow heel part, a plurality of

driver guiding tubes vertically mounted in the bottom wall of the heel part with their ends flush with the outer surface of the said 45 wall, a driver carrying bar guided for reciprocation within the heel part, a plurality of drivers mounted on the driver bar and received within the driver guiding tubes, and springs arranged between the bottom wall 50 and the bar for maintaining the drivers normally in retracted position in the driver guiding tubes, said heel part being provided with an opening affording access to the bar to effect operation of the drivers. 55

10. A shoe forming and making last comprising a forepart, a heel part having a fastening guiding passage terminating in the bottom surface of the last, and means associated with the said fastening guiding passage at its opposite end to retain a fastening in the fastening guiding passage during the use of the last in the manufacture of a shoe. 60

11. A shoe forming last comprising a 65 forepart and a heel part and having a fastening receiving passage formed in the heel part, a driver in said passage, and means in the heel part for maintaining the end of the driver at a predetermined distance from 70 the last bottom so that the head of a fastening in said passage may rest against the driver with its point projecting beyond the last bottom to receive and retain in position the shoe sole during the lasting operation, 75 the last being provided with an opening in its cone to afford access to the driver and enable the driver to be operated to drive the fastening through the sole into a heel while the shoe is still in undisturbed lasted 80 condition upon the last.

In testimony whereof I have signed my name to this specification.

MELBOURNE W. WHITE.
